UNITED STATES PATENT OFFICE.

JOHN W. COWELL, OF CHICAGO, ILLINOIS.

OIL-BURNER.

1,377,669.

Specification of Letters Patent. Patented May 10, 1921.

Application filed October 28, 1919. Serial No. 333,872.

To all whom it may concern:

Be it known that I, JOHN W. COWELL, a citizen of the United States, residing at Chicago, county of Cook, State of Illinois, have 5 invented a certain new and useful Improvement in Oil-Burners, and declare the following to be a full, clear, and exact description of the same, such as will enable others skilled in the art to which it pertains to 10 make and use the same, reference being had to the accompanying drawings, which form a part of this specification.

My invention has for its object to produce a burner for liquid fuel in which the 15 liquid will be effectively vaporized and effectively mixed with air so as to secure practically perfect combustion; in which the size of the flame may be regulated without affecting the efficiency; and which shall be 20 provided with a pilot light supplied with fuel from the main source so that the burner will automatically light upon the proper manipulation of the main controlling device.

A further object of the present invention 25 is to provide an automatic safety device which, in case the burner should happen to become flooded, will cause the fuel to be shut off.

The various features of novelty whereby 30 my invention is characterized will herein-after be pointed out with particularity in the claims; but, for a full understanding of my invention and of its objects and advantages, reference may be had to the following 35 detailed description taken in connection with the accompanying drawings, wherein:

Figure 1 is a top plan view of a burner arranged in accordance with my invention, parts being broken away in order more 40 clearly to show underlying parts;

Fig. 2 is an end elevation of the burner, the safety device being shown in section;

Fig. 3 is a view of the burner partly in side elevation and partly in longitudinal 45 vertical section;

Fig. 4 is a section taken approximately on line 4—4 of Fig. 3;

Fig. 5 is a view partly in elevation and partly in section of the flow-regulating 50 mechanism;

Fig. 6 is a perspective view of a fragment

of one of the grids forming the combustion chamber; and

Fig. 7 is a vertical transverse section on an enlarged scale through one of the fuel 55 troughs with the wick and vaporizing element associated therewith.

Referring to the drawings, 1 represents a flat horizontal base or plate, supported on suitable legs, 2. The plate is provided with 60 a plurality of deep depending ribs; there being, in the arrangement shown, three longitudinal ribs, 3, and transverse ribs, 4. Each rib is hollowed out in the upper face so as to provide a comparatively deep trough 65 or groove, 5, and running through each rib, lengthwise thereof and at some distance below the groove, is a fuel passage, 6, connected at intervals with the corresponding groove by means of small ports or passageways, 7.

In each groove there is arranged on edge a thin flat wick, 8, preferably made of an asbestos core held in a perforated U-shaped sheet metal sheath, 9, overlying the upper edge and extending down the sides. A 75 coiled wire, 10, is threaded through each wick, as shown, so that a portion thereof extends down into the groove and the remainder projects above the top of the latter. Air holes or twyters, 11, extend diagonally through 80 the member 1 on each side of each of the ribs along the base of the latter so as to terminate at their inner ends in the vicinity of the top of the corresponding groove. The longitudinal fuel conduits, 6, are connected 85 with the transverse conduits. Fuel is delivered from the under side of the burner at the intersection of the central transverse and longitudinal ribs and conduits therein; there being at this point a fitting, 12, to which a 90 flexible supply pipe, 13, leads. A small pencil-shaped wick, 14, extends upwardly from within the fitting 12 to a point in the vicinity of the plane of the upper edges of the wicks 8; the wick, 14, being for the purpose 95 of maintaining a pilot light as will herein-after be explained.

Above the plate 1 is constructed a combustion chamber made up of a plurality of compartments communicating with each 100 other and with the outside atmosphere at a large number of points. This combustion

chamber is preferably made up of a series of flat grids, 15, laid one upon the other, the lowermost element resting upon the plate 1. The stack of grids is clamped together and to the plate 1 by means of a cover plate, 16; bolts, 17, passing down through the cover plate and through the plate 1. The grids are so formed that they produce above each trough-like groove a chimney, 18. Each of the grids is provided with numerous small grooves, 19, cut across one or both faces of the same so as to permit air to enter each of the chimneys from all sides and at a great many points and place the chimneys in communication with each other through the compartments, 20 of the combustion chamber lying intermediate between the chimneys. The stack of grids is inclosed at the sides and at the ends 25 in a hood or apron, 21, extending downwardly from the cover plate and spaced apart from the sides of the stack. Air may thus rise in the space within the hood around the stack and enter the combustion chamber at all elevations.

The fuel is supplied from a reservoir, 22, through a flexible pipe, 23, into the top of a float chamber, 24, shown in detail in Fig. 5. The pipe 13, which leads to the burner, is connected to the bottom of the float chamber. The discharge end of the pipe 23 is controlled by a needle valve, 26, provided with a longitudinal slot, 27, through 30 which passes a stationary pin, 28; the pin and slot permitting the valve to rise and fall but preventing it from turning, and therefore making it possible to secure a tight fit of the valve in a definite angular position and then prevent the valve from turning out of that position. The valve rests on a swinging lever, 29, preferably resilient; and one end of the lever rests upon a float, 30.

The liquid in the float chamber and the liquid in the burner or the connections leading to the burner from the float chamber will always be at the same level. Furthermore, when the liquid in the float chamber reaches a predetermined level therein, the valve, 26, will be closed. Therefore, by raising or lowering the float chamber as a whole the liquid level in the burner and connections will be correspondingly raised or lowered. In the arrangement shown, the float chamber has an upwardly-projecting bracket, 31, provided with a vertical rack, 32. A pinion, 33, fixed to a shaft, 34, mounted in suitable stationary bearings, meshes 50 with the rack. The shaft, 34, is provided with a handle, 35, by means of which it may be actuated. It will be seen that by turning the handle the float chamber may be raised or lowered as desired. The float chamber is provided with one or more

laterally-projecting ears, 37, through which vertically-adjustably headed posts or screws, 38, pass loosely. In the arrangement shown, the members 38 are screws screw threaded into the extreme end of or an extension of 70 the plate 1. The parts are so proportioned that when the float chamber is lowered as far as it will go the liquid level in the burner will be below the wick-containing grooves. Therefore at this time the only 75 wick that will be immersed in liquid fuel is the pilot wick, 14, and therefore the pilot light will remain burning after the main burner has been turned off through the lowering of the liquid level below the main 80 wicks when the float chamber is lowered. The adjustable posts, 38, are so adjusted that the float chamber cannot be raised high enough to cause the fuel to overflow from the wick-containing grooves, or they 85 may be adjusted so as to limit the lift of the float chamber to a level which will give a predetermined character of flame.

In case the controlling valve 26 should happen to fail it might be that the burner 90 would be flooded. To prevent this I have provided a safety device which will shut off the supply of fuel whenever the float chamber becomes filled to a predetermined abnormal level. To this end I have placed in 95 the pipe 23, a valve, 40, having an actuating handle or bar, 41, on one end of which is a counterweight, 42, and on the other end of which is hung a receptacle, 43. When the receptacle is empty the counterweight is able 100 to hold the valve 40 open. A pipe, 44, leads from the predetermined danger level in the float chamber into the top of the member 43. The pipe 44 may either be a flexible pipe or it may be a rigid pipe having a vertical leg, 105 45, extending loosely downwardly into a sleeve, 46, in the top of the receptacle, 43, so as to permit the float chamber to be raised and lowered for starting and stopping the burner and adjusting the flame without affecting the member 43. In case the liquid in the float chamber rises to the danger level, liquid begins to flow through the pipe 44 into the receptacle, 43, and, as soon as sufficient liquid is collected therein, the receptacle descends from the full line position in Fig. 2 to the dotted line position and closes the valve 40.

It will thus be seen that I have produced a burner of few, simple, strong parts, so that 110 the burner cannot easily get out of order. The fuel is supplied evenly along a line equal to the combined lengths of all of the wick-containing grooves. The spiral wires have their upper portions lying in the flame 115 and their lower portions immersed in the fuel when the burner is turned on, so that heat is rapidly conducted by the wires and delivered to the liquid fuel with the result that vapor is rapidly and efficiently gen- 120 125 130

erated. As the vapor is generated it starts to rise through the chimneys, mixing at the very outset with air drawn in through the air ports or twyers, 11, and afterward entering 5 countering myriads of tiny streams of air flowing laterally through the interstices in the stack of grids. Consequently there is no point in the large combustion chamber at which unconsumed gases or vapors can fail to receive an adequate supply of air to insure 10 combustion. Consequently almost perfect combustion is obtained without the formation of smoke. Furthermore, the formation of soot is prevented because of the facilities for perfect combustion and the presence of hot grids which prevent the cooling of the minute particles which, upon coming in contact with cool surfaces become soot. By making the grids in the form of 15 flat plates lightly grooved to form air passages, a solid structure is obtained which will not warp or become distorted under the action of heat and thus reduce the efficiency resulting from an accurate original proportioning of the parts of the combustion chamber and air channels.

It will also be seen that by simply turning the controlling handle for the float chamber, the burner may be turned on and off and the 20 flame be raised and lowered; the pilot light remaining burning when the main burner is turned off and thus not only providing a light for the main burner when the latter is again turned on, but keeping the walls of the compartments of the combustion chamber more or less warm so that the burner 25 need not be started in a cold condition after it has once been lighted; thus avoiding an initial discharge of smoke or soot deposit either or both of which might result and continue for a short time in starting a cold burner.

It will furthermore be seen that there is no danger of accidental flooding of the 30 burner unless both the float-controlled valve and the main shut-off valve happen to be out of order at the same time; this being a contingency which is not very apt to take place.

While I have illustrated and described 35 with particularity only a single preferred form of my invention, I do not desire to be limited to the exact structural details thus illustrated and described; but intend to cover all forms and arrangements which 40 come within the terms employed in the definitions of my invention constituting the appended claims.

I claim:

1. A burner comprising a plate having 45 fuel troughs in its upper surface, wicks in said troughs, and a combustion chamber comprising a stack of flat grids resting directly upon each other and on said plate, each grid having a face grooved or scored 50 across the elements thereof at numerous

points to form a multitude of air passages into the combustion chamber and between the compartments thereof.

2. A burner having a fuel-receiving trough, a wick set on edge in the trough, 70 and a heat conductor threaded through the wick and having parts extending above the latter and other parts extending down into the trough.

3. An element for an oil burner comprising 75 a long flat wick and a wire spiral threaded through the same in the vicinity of a long edge so that the axis of the coil lies parallel with said edge and the coil embraces said edge.

4. In combination, a liquid-fuel burner having a fuel trough, a main wick in said trough, a supply conduit opening into the bottom of the trough, a pilot wick arranged in the vicinity of the main wick and extending downward into said conduit, a source of liquid supply connected to said conduit, and controlling means adapted to maintain a liquid level at times sufficiently high in the trough to wet the main wick 85 and at other times low enough to lie below the main wick and above the lower end of the pilot wick.

5. In combination, a liquid fuel burner, 90 a source of fuel supply, a constant level device for controlling the flow of fuel from said source to the burner, a shut-off valve between said source and said burner, and additional means controlled by fuel rising above a predetermined level for closing 100 said shut-off valve.

6. A burner comprising a single plate having intersecting longitudinal and transverse fuel troughs in its upper surface and a series of interconnected fuel conduits or passages formed in the plate below the troughs, each trough being connected with the underlying conduit by means of a plurality of small openings distributed throughout the length of the trough, and a supply pipe connected to said conduits.

7. A burner comprising a single plate having intersecting longitudinal and transverse fuel troughs in its upper surface and a series of interconnected fuel conduits or passages formed in the plate below the troughs, each trough being connected with the underlying conduit by means of a plurality of small openings distributed throughout the length of the trough, and a supply pipe connected to said conduits at about the middle of the burner.

8. A burner comprising a single plate having intersecting longitudinal and transverse fuel troughs in its upper surface and 125 a series of interconnected fuel conduits or passages formed in the plate below the troughs, each trough being connected with the underlying conduit by means of a plurality of small openings distributed through- 130

out the length of the trough, and a supply pipe connected to said conduits, said plate having air openings or twyers extending upwardly therethrough on opposite sides of each trough and arranged at an angle to the vertical so as to cause the incoming air to flow across the tops of the troughs.

9. A burner comprising a single plate having intersecting longitudinal and transverse fuel troughs in its upper surface and a series of interconnected fuel conduits or passages formed in the plate below the troughs, each trough being connected with

the underlying conduit by means of a plurality of small openings distributed throughout the length of the trough, and a supply pipe connected to said conduits at about the middle of the burner, said plate having air openings or twyers extending upwardly therethrough on opposite sides of each trough and arranged at an angle to the vertical so as to cause the incoming air to flow across the tops of the troughs. 15 20

In testimony whereof, I sign this specification.

JOHN W. COWELL.
